UNITED STATES PATENT OFFICE.

JAMES A. HERRICK, OF NEW YORK, N. Y.

GAS-PRODUCER.

998,614.

Specification of Letters Patent. Patented July 25, 1911.

Application filed July 24, 1908. Serial No. 445,071.

To all whom it may concern:

Be it known that I, JAMES A. HERRICK, a citizen of the United States, residing in the city of New York, county of New York, 5 and State of New York, have invented certain Improvements in Gas-Producers.

This invention contemplates improvements in the manufacture of gas by means of a duplex gas producer having a regenerative action. It is designed to make coke in one producer while the usually waste gases given off during this operation are carried down, enriched, purified and made permanent in the other properly coked producer, the 10 operation being reversed when it becomes desirable to feed fresh fuel, which is charged into the producer previously effecting the secondary operation. To carry out this operation in the most efficient and economical manner, I have devised a structure having characteristic features which will fully appear in the following description and the accompanying drawings in illustration thereof.

25 In the drawings, Figure 1 is a sectional elevation of a continuous duplex producer designed for the practice of my invention; Fig. 2 is a transverse sectional view taken on the line 2—2 of Fig. 1, and Fig. 3 is an 30 irregular vertical sectional view approximately on the line 3—3 of Fig. 2.

As illustrated in the drawings, the preferred form of the producer comprises the base A having the two cones A¹, surrounded 35 by the circular basins A², which are divided by the central ridge A³, the ridge being lower than the general level of the base so that there is communication between the basins. Pillars A⁴, formed in the base below the general level thereof, support the 40 producer bodies B centrally above the respective cones A¹, channels A⁵ being formed in the base so as to communicate with the basins to receive water therefrom and seal 45 the joints at the bottoms of the bodies.

Within the bottom or ash hopper of each body are the twyrs comprising the boxes C radiating from the terminus of a blast pipe D. The terminus of each pipe D is centrally disposed with reference to the corresponding body and discharges into the several boxes, which latter discharge through the apertures C¹, C² and C³ by which distribution is made to the fuel in 50 process of combustion. The pipes D are

connected with opposite sides of a valve box E and in communication with this valve box are the blower F and the gas take off pipe G, the latter delivering to a scrubber G¹ and the flow being facilitated by a suction blower G². Blower F and suction blower G² are approximately balanced, that is, the suction blower is of a capacity such that the quantity of gas withdrawn from the producers will bear a direct relation to the amount of blast forced therein by the blower F.

A simple form of valve, as the butterfly valve H, is located within the box and operated through an arm H¹ connected therewith and with a hand operated rod H², the valve being designed to place the blower in direct communication with either of the pipes D and at the same time establish communication between the other of these pipes and the gas take off pipe G. The valve box is provided with hollow walls forming chambers E¹ containing water for cooling purposes.

To flow water over the twyrs and cool them, the boxes C have formed in their ridges the notched channels C⁴ and the conical top of the vertical part D² of the pipe D, which joins these boxes, is provided with the channel D³ which communicates with the channels C⁴. Perforated pipes C⁵ lie in the channels C⁴ and extend inwardly through the walls of the bodies from the circular pipes C⁶ exterior to the bodies, the pipes C⁶ being connected by branches C⁷ with a valve box C⁸ containing a valve C⁹ by which water may be directed into either or both sets of pipes.

A passage I connects the upper parts of the producers and in this passage is located the double expanding tube or nozzles J (analogous to a Venturi tube in the form illustrated) having mouths communicating with the respective producer bodies. In the contracted throat J¹ of this tube are disposed the outlets or nozzles K¹ of tubes K which are connected with the valve box L. This box contains a butterfly valve M, connected by an arm M¹ with the rod H³, and has communicating therewith a pipe N for the introduction of fluid hydro-carbon and steam, so that when the valve H is set to induce flow of gas from say the left hand to the right hand producer, the valve M is set to induce the flow of steam and fluid 100 105 110

hydro-carbon into the right hand producer to accelerate the action and enrich the gas. The accelerator serves not only to facilitate the flow and enrich the gas, but also to keep clean the passage connecting the producers.

The pipe N is connected, by a branch N¹, containing a valve N², with a steam pipe O, which leads to the blower F and contains a valve O¹ between the blower and the branch N¹. The pipe N is also connected with a branch N³ containing a valve N⁴ which controls the flow from a funnel N⁵ communicating with the branch, oil being dropped 15 into the funnel from a pipe P.

A purge pipe Q is provided with the branches Q¹ which communicate with the respective producers near the tops thereof, the pipe having the test cock Q² and the removable top Q³.

Hoppers R, connected with the tops of the respective producers, provide means for charging them with fuel.

In operation, coarse clean ashes are filled 25 into both producer bodies so as to entirely surround and cover the twyer structure. Wood and coke are then placed on the ash beds and ignited; the reversing valves being set vertically so as to permit air to draw 30 through both pipes D from the now fully open blower F and the purge pipe Q being uncovered to provide draft and permit the escape of smoke therethrough. When the fires in the respective producers have been 35 fed until beds of hot coke are provided, the sealing basins are filled with water to the proper level to immerse the bottoms of the bodies, steam blast is gradually added, and soft coal and coke are fed to the fires until, 40 the gas evolved will burn with the production of a flame. The top of the purge pipe is then closed, the reversing valves are thrown so as to carry on the initial production of gas in the producer desired, and the raw gas 45 is carried into the second producer and downwardly through the bed of hot coke in the bottom thereof, issuing through the twyers and the corresponding pipe D to the gas take-off pipe G. Thus the raw gas from 50 the first producer is subjected in the second producer to a treatment which gasifies the tarry matter carried therewith, breaks up excessive CO₂, with the formation of CO, enriches the gas with production of large increments of hydrogen gas, making semi-water gas, and delivers it in superior condition, with less work to be done in the scrubber and with less disposition to clog the action of an engine in which it may be used. 55 After this operation has been carried on until the hot coke in the producer effecting the secondary operation has become partly cooled, the reversing valves are thrown and fuel is fed into the producer, which by the 60 reversal of the valves becomes the primary

producer, from which the gas evolved is carried through the coke bed of the adjacent producer to the gas take-off pipe G.

It is to be understood that fuel is always fed into the producer used as a primary producer so that when it becomes secondary by the reversal of the operation, it will contain a bed of hot coke, which acts upon the raw gases delivered thereto from the opposite producer. Hence any tar that has not previously been decomposed and changed into permanent gas, as also the soot carried therewith, is intercepted. Any tarry matter of value which lodges in the coke bed and is not gasified by reason of the lack of free oxygen, is changed into gas upon the reversal of the operation and the introduction of oxygen. This mode of operation avoids the necessity of "purging off" and making up fresh coke fires in the usual manner. It 85 provides means for making a high grade and clean semi-water gas with an inferior quality of fuel. Water gas can be made directly as distinguished from former operations. There is little leakage or undesirable introduction of air because the operation is carried on by combined pressure and suction which are approximately balanced.

Having described my invention, I claim:

1. In apparatus of the class described, in combination, a pair of producers, passage ways connecting said producers top and bottom, a blast distributing and gas collecting box in each of said producers, conduits connecting one of said passage ways with the central portions of both of said boxes, a valve chamber formed in said passage way, a blast pipe leading into said valve chamber, a gas exit pipe leading therefrom, and a valve in said valve chamber adapted to connect one of said producers with said blast pipe and the other of said producers with said gas exit pipe.

2. In apparatus of the class described, in combination, a pair of producers, passage ways interposed between said producers at the top and bottom portions thereof, a blast distributing and gas collecting box in each of said producers, a conduit extended between the lowermost of said passage ways and the central portion of each of said boxes, a valve chamber formed in said last mentioned passage way, a blast pipe leading into said valve chamber, a gas exit pipe leading therefrom, and a reversible valve located in said valve chamber adapted to connect one of said boxes with the blast pipe and the other of said boxes with the gas exit pipe.

3. In apparatus of the class described, in combination, a pair of producers, passage ways connecting said producers top and bottom, a valve chamber located in the lowermost of said passage ways, a blast distributing and gas collecting box located in each of said producers, a blast pipe leading

- into said valve chamber, a gas discharge pipe leading therefrom, conduits connecting the last mentioned of said passage ways with the central portions of each of said boxes, 5 a reversible valve in said valve chamber adapted to connect one of said boxes with said blast pipe and the other of said boxes with the gas discharge pipe, an open ended box located in the other passage way and 10 spaced from the walls thereof, a pair of nozzles located in said box, said nozzles pointing in opposite directions, a source of steam supply, a valve chamber, a pipe leading from said valve chamber to each of 15 said nozzles, and a valve in said valve chamber adapted to connect one of said nozzles with said source of steam supply to the exclusion of the other.
4. In apparatus of the class described, in 20 combination, a pair of producers, passage ways extended between said producers at the top and bottom portions thereof, a valve chamber formed in the lowermost of said passage ways, a blast distributing and gas 25 collecting box located in each of said producers near the lower end thereof, a conduit connecting said valve chamber with each of said boxes, a blast pipe leading to said valve chamber, a gas discharge pipe leading there- 30 from, a valve in said valve chamber adapted to connect said blast pipe with one of said boxes, and the other of said boxes with said gas discharge pipe, an open ended box extending through the other passage way, 35 said box being spaced from the walls thereof, means for discharging steam alternately in opposite directions to said box, a source of steam supply, a valve chamber, and means in said valve chamber for controlling 40 the flow of steam to said steam discharging means.
5. In apparatus of the class described, in 45 combination, a pair of producers, a blast distributing and gas collecting box located in each of said producers near the lower portion thereof, a blast pipe, conduits connecting said blast pipe with each of said blast distributing and gas collecting boxes, a valve interposed between said blast pipe and said 50 conduits whereby blast may be caused to flow through one thereof, the other thereof being closed to the blast, a gas discharge conduit connected with said first mentioned conduits, said valve being adapted to connect one of the latter with the blast distributing and gas collecting box to which the blast has been shut off, a passage way connecting the upper portion of said producers, an open ended box extending through 55 said passage way, a pair of nozzles located in said box and opening in opposite directions, means for discharging steam through said nozzles, mechanical means for forcing a blast through said blast pipe, and mechanical means for withdrawing gas through 60 said gas discharge pipe.
6. In apparatus of the class described, in combination, a pair of producers, an apertured box located in the lower portion of each of said producers having a plurality of radially extending legs, a blast pipe, a conduit connecting said blast pipe with each of said boxes adjacent the point of jointure of said legs, a gas discharge conduit connected with said last mentioned conduit, 70 means whereby blast may be forced through one of said boxes to the exclusion of the other and whereby gas may flow from the other of said boxes to said gas exit conduit, a blower for forcing the blast through said 75 blast pipe, and a suction device for withdrawing gas through said gas exit conduit.
7. In apparatus of the class described, in combination, a pair of producers, passage ways connecting the upper and lower ends 80 of said producer, a blast pipe leading to one of said passage ways, a gas exit pipe leading therefrom, means for shutting off the flow of blast to one of said producers and permitting a flow of gas from the other, a 85 gas distributing device in each of said producers, means for discharging water upon each of said gas distributing devices, and means for alternately rendering said water distributing means operative.
- In witness whereof I have hereunto set my name this 11th day of July, 1908, in the presence of the subscribing witnesses.
